US0D1033438S

(12) **United States Design Patent** (10) Patent No.: **US D1,033,438 S**
(45) Date of Patent: ** Jul. 2, 2024

(54) **TABLET CASE**

(71) Applicant: **SHENZHEN ZOLON TECHNOLOGY CO., LTD.**, Shenzhen (CN)

(72) Inventors: **Deqiang Dong**, Shenzhen (CN); **Yuzhuo Wang**, Shenzhen (CN); **Xinpeng Guo**, Shenzhen (CN); **Liting Lu**, Shenzhen (CN)

(73) Assignee: **SHENZHEN ZOLON TECHNOLOGY CO., LTD.**, Shenzhen (CN)

(**) Term: **15 Years**

(21) Appl. No.: **29/838,180**

(22) Filed: **May 11, 2022**

(30) **Foreign Application Priority Data**

Jan. 21, 2022 (CN) 202230041667.1

(51) LOC (14) Cl. **14-02**

(52) U.S. Cl. **148/4.6**; D14/440; D14/385; D18/12
